PIVOTED LEG INSTRUMENT

Filed May 17, 1943

UNITED STATES PATENT OFFICE

2,364,806

PIVOTED LEG INSTRUMENT

James Nash, Sheboygan, Wis., assignor to William H. Murphy, executor of Harry De Lisle, deceased, doing business as Engineering Sales Company, Sheboygan, Wis.

Application May 17, 1943, Serial No. 487,306

5 Claims. (Cl. 33—153)

The present invention relates to pivoted leg instruments of the class of which dividers, compasses and calipers may be considered as representative members. This invention may be considered as an improvement upon the device forming the subject matter of my copending patent application Serial No. 461,132, filed October 7, 1942, for Drafting instruments and the like.

Although the present invention is illustrated as embodied in a drafting or navigating compass, it will be appreciated that most of the novel features may to advantage be embodied in dividers, calipers or other pivoted leg instruments.

One of the objects of the present invention is to provide a novel pivoted leg type instrument having the advantages of the device forming the subject matter of the before mentioned copending application and which in addition has simple means for quickly and easily aligning the tips at the free ends of the legs.

Another object of the present invention is to provide a novel pivoted leg instrument formed principally of molded plastic pieces, which is economical to manufacture in large quantities, is neat in appearance, is easily and positively adjusted for transverse misalignment, which will remain set to a desired dimension, and which has a smooth soft action at the pivot, thus enabling quick and easy adjustment of the tips to a desired setting.

Yet another object is to provide a novel compass having the above advantages, and further being adapted to have a lead chuck which does not require loosening and tightening a clamp in order to move the lead inwardly or outwardly.

Other objects and advantages will become apparent from the following description of a preferred embodiment of my invention illustrated in the accompanying drawing in which similar characters of reference refer to similar parts throughout the several views.

Referring to the drawing:

Figure 1 is a perspective view of a compass incorporating my invention;

Fig. 2 is a sectional view drawn to a larger scale, which may be considered as taken in the direction of the arrows substantially along the line 2—2 of Fig. 1;

Fig. 3 is a sectional view of the pivot mechanism taken in the direction of the arrows along the line 3—3 of Fig. 2;

Fig. 4 is a detail view of the leg tips shown in side elevation; and

Fig. 5 is a horizontal sectional view through

the point chuck. This view is taken along the line 5—5 of Fig. 4, looking downwardly as indicated by the arrows.

The principal elements of the pivoted leg instrument illustrated in the drawing are a pair of legs indicated by the numerals 10 and 12. These legs are pivoted at their upper ends, while their free lower ends may both be equipped with points to form dividers, or one leg 10 may have a chuck 14 to receive a point 16, while the other has a lead chuck 18 to receive a pencil lead 20 to form a compass. In any event, I prefer that both legs be molded from a hard plastic substance, as an example, a phenol-formaldehyde condensation resin such as "Bakelite" for instance, because of manufacturing economies inherent in the use of such materials and because of their lightness, resistance to corrosion, and low specific heat which prevents the instrument feeling cold to the touch. 10 If desired, the legs may of course be formed of other materials.

A cylindrical passage 22 extends upwardly into the free end of the leg 10, preferably slightly obliquely and is adapted to receive one end of 25 the steel or other hard metal point 16. The passage 22 is slightly oblique so that the lower tip of the point 16 can be set to a position such that a line from the tip to the pivot will not pass through the leg portion 10. This, together with 30 a similar setting of the lead chuck 18 enables the lead 20 and tip 16 to be brought together without interference between the leg portions. The point 16 is retained in position by a setscrew 24 threaded transversely into the side of the leg 35 in a position such that it projects into the passage 22.

The leg 12 can similarly be provided with a sharp point 16, or as shown, the end of the leg may have a metal sleeve 26 molded in at the time 40 of forming, the sleeve being shaped and dimensioned to receive the end of a mechanical pencil chuck, the chuck shown being of the type used in "Autopoint" pencils manufactured by the 45 Autopoint Company of 1801 West Foster Avenue, Chicago, Illinois. Preferably the sleeve 26 is set into the leg 12 at a slightly oblique angle, as is the point 16, so that the lead 20 and point 16 will come substantially together when the legs 50 are closed. By properly shaping the portion of the leg 12 immediately above the chuck 18, a pleasing appearance can be maintained even though the chuck is somewhat more bulky than ordinarily used clamp type chucks. Although a 55 clamp type chuck can be used if desired, it is be-

lieved that the added convenience associated with the chuck shown justifies its use.

At their upper ends the legs 10 and 12 are shaped to provide discs 26 and 28, respectively, with their centers offset into substantial alignment with the inner edges of the legs. The discs are somewhat less than one half the thickness of the legs and are offset with their outer faces in alignment with one of the faces of the legs, so that when the inner faces of the discs are placed contiguous to each other with a slight spacing, the legs 10 and 12 are in alignment.

As shown, the inner face 30 of the disc 28 is highly concave, its center being a matter of thousandths of an inch or so below the edge. The similar face 32 of the disc 26 is provided with two spherical knobs 34 spaced about half the distance from the center to the edge of the disc. These knobs are arranged about 60° each side of the inner edge of the leg and in a position above the center of the disc. In a similar position below its center, the disc 26 is threaded to receive a short adjustment screw 36 extending therethrough transversely, so that the inner end of the screw 36 and the knobs 34 are substantially equally spaced from each other and from the center of the face 32. The inner end of the screw 36 is cup pointed for a reason to be explained presently.

The discs 26 and 28 pivot about a cylindrical bushing 38 which fits into cylindrical recesses 40 counterbored or molded into the faces 30 and 32. The bushing therefore prevents lateral shifting of the two legs relative to each other, but permits pivotal movement. A thin washer 42 is located around the bushing 38 in a position between the faces 30 and 32. This disc bears with its periphery against the concave face 30 and therefore forms a circular line contact which gives a smooth pivotal movement between the disc 28 and the washer 42, while acting as a brake to maintain any desired setting of the points. This circular line contact also prevents rocking of one leg relative to the other at the pivot point. The washer 42 has a conical dent formed in the face adjacent face 30, thus forming a projection 44 on the opposite side, so located as to fit into the cup point of the adjustment screw 36. The adjustment screw therefore causes the washer 42 to rotate with leg 10.

The two legs are clamped together by a rivet 46 which extends centrally through the discs 28 and 26 in the order named and through the bushing 38. Between the rivet head and the outer face of the disc 28 a thin washer 48 serves to reduce friction and prevents cutting of the face of the disc 28 by the inner surface of the rivet head. The opposite end of the rivet extends through a hole in the center of a star shaped spring 50, having its legs bearing against the outer face of disc 26, and is rolled over to form a shoulder 52 to prevent separation of the spring from the rivet.

At the time the shoulder 52 is formed, the spring 50 is slightly compressed; it therefore presses the faces 30 and 32 against the washer 42 with an even pressure.

The construction described is such that the rivet and spring serve to hold the two legs together, the bushing 38 and recesses 40 serving to prevent lateral shifting, while the line contact between the concave face 30 and washer 42 prevents wobbling and insures a smooth pivoting action. Further the three point contact—the knobs 34 and screw 36—between the leg 10 and

washer 42 enables the tips 16 and 20 easily to be shifted into lateral alignment simply by turning the screw 36 inwardly or outwardly slightly. Also, the cup point in the screw 36 fitted over the projection 44 in the washer 42 prevents relative rotation between these elements and thus prevents the possibility that the end of the screw might cut a groove in the washer after extensive use of the instrument.

Having described my invention in connection with a preferred embodiment thereof, what I claim as new and useful and desire to secure by Letters Patent is:

1. A pivoted leg instrument comprising a pair of legs having similar circular disc-like contiguous faces formed at their upper ends, one of said faces being slightly concave, a hinge pin extending through and joining said legs in a position substantially centrally of said faces, a thin flat washer surrounding said pin and located between said faces and bearing against said concave face at its periphery, said washer being spaced from said concave face at points other than its periphery by reason of the concave nature of said face, the other of said faces having projections bearing against said washer, one of said projections being adjustable to change the angle between the last said face and said washer, and resilient means cooperating with said hinge pin tending to urge said faces toward each other.

2. A pivoted leg instrument comprising a pair of legs having similar circular disc-like contiguous faces formed at their upper ends, a hinge pin extending through and joining said legs in a position substantially centrally of said faces, a thin flat washer surrounding said pin and located between said faces, one of said faces being so formed that only the periphery of said washer bears thereagainst, the other points of said washer being spaced from said face, resilient means cooperating with said hinge pin tending to urge said faces toward each other, and the other of said faces having projections bearing against said washer, one of said projections being adjustable.

3. A pivoted leg instrument comprising a pair of legs having similar circular disc-like contiguous faces formed at their upper ends, a hinge pin extending through and joining said legs in a position substantially centrally of said faces, a thin flat washer surrounding said pin and located between said faces, one of said faces being so formed that only the periphery of said washer bears thereagainst, the other points of said washer being spaced from said face, resilient means cooperating with said hinge pin tending to urge said faces toward each other, and the other of said faces having three spaced projections bearing against said washer, one of said projections being adjustable.

4. A drafting instrument or the like comprising a pair of legs having similar circular disc-like contiguous faces formed at their upper ends, one of said faces being slightly concave, a hinge pin extending through and joining said legs in a position substantially centrally of said faces, a thin flat washer surrounding said pin and located between said faces and bearing against said concave face at its periphery, said washer being spaced from said concave face at points other than its periphery by reason of the concave nature of said face, the other of said faces having spaced points bearing against said washer, means to prevent relative rotation between the last said

face and said washer, and resilient means co-operating with said hinge pin tending to urge said faces toward each other.

5. A drafting instrument or the like comprising a pair of relatively angularly movable elements pivoted together, a pivot pin passing through said elements at the pivoting axis, resilient means biasing said relatively movable elements toward each other, one of the contiguous faces of said relatively movable elements being slightly con-

cave, the other of the contiguous faces having three projections substantially located at the apexes of an equilateral triangle, one of said projections being adjustable as to length, a thin flat washer located between said faces substantially coaxial with said pivot pin, and means to prevent relative rotation between said washer and the face having the projections.

JAMES NASH.

CERTIFICATE OF CORRECTION.

Patent No. 2,364,806.

December 12, 1944.

JAMES NASH.

It is hereby certified that error appears in the printed specification of the above numbered patent requiring correction as follows: Page 2, first column, line 14, for "highly" read --slightly--; and that the said Letters Patent should be read with this correction therein that the same may conform to the record of the case in the Patent Office.

Signed and sealed this 15th day of May, A. D. 1945.

Leslie Frazer

(Seal)

Acting Commissioner of Patents.
